UNITED STATES PATENT OFFICE.

BELA LACH, OF VIENNA, AUSTRIA-HUNGARY.

TREATMENT OF OILS.

1,104,906.

No Drawing.

Specification of Letters Patent. Patented July 28, 1914.

Application filed June 5, 1913. Serial No. 771,873.

To all whom it may concern:

Be it known that I, BELA LACH, a subject of the Austro-Hungarian Emperor, and residing at 71 Ungargasse, Vienna, III, 5 Austria-Hungary, have invented certain new and useful Improvements in the Treatment of Oils, of which the following is a specification.

This invention relates to the treatment of 10 fats and oils in order to remove therefrom impurities, particularly of a gelatinous and albuminous nature; and it comprises a process of treating such fats and oils with formaldehyde and with steam in order to 15 remove from the fats and oils such impurities; it further comprises a process of treating the resulting purified oil in order to remove therefrom any excess of formaldehyde and to effect a further purification of the oil 20 by means of hydrogen, and particularly by treatment with nascent hydrogen generated in the oil mass, all as more fully hereinafter set forth and as claimed.

According to processes where strong re- 25 agents such as concentrated acids or alkali are used for refining oil, the oil is attacked to a greater or less extent, causing losses of the oil, and often causing the formation of objectionable by-products. Moreover, the 30 removal of impurities, especially those of a gelatinous and albuminous nature, presents particular difficulties. According to the process of the present invention, oils are freed from such impurities and also from 35 objectionable compounds which cause color and odor of the oils without the formation of objectionable by-products and losses resulting therefrom.

According to the process of the present 40 invention the oils and fats are boiled by admitting steam into the oil in an open vessel and with the addition of small amounts of formaldehyde to the hot material. The formaldehyde is advantageously added in 45 small amounts, or by passing vapors of formaldehyde into the oil. The formaldehyde added may be of the form commercially known as formalin (40% solution) or the polymerized form known as paraformaldehyde. The amount added should be sufficient 50 (usually less than 1% is sufficient) to coagulate and precipitate the gelatinous and albuminous matters. Usually these substances are removed after a treatment lasting for 55 about one-quarter to one-half an hour, by which the albuminous materials are sep-

arated in an insoluble form and precipitated. With oils containing only a small amount of such gelatinous and albuminous matters, only a small amount of formaldehyde is 60 necessary. With oils containing larger amounts of such substances correspondingly more formaldehyde is necessary. With some oils the formaldehyde in addition to removing such materials appears to combine with 65 the oil itself, partly at least, apparently in the form of unstable compounds.

In order to remove any excess of formaldehyde which may be retained in the oil after the preceding treatment and to accomplish further purification, the fats and oils when still boiling are treated with about 1 to 2% of a metal powder and with a mineral acid to generate hydrogen therefrom. As such metal powders may be mentioned, for 70 example, zinc dust and iron filings. If zinc dust is used it penetrates the whole mass of the fat and oil so that upon addition of acid, such as hydrochloric or sulfuric acid, hydrogen is generated throughout the mass in 75 a nascent state. Instead of generating the hydrogen in this manner, other suitable processes of hydrogenation can be used. By the action of this hydrogen formed intimately in contact with the oil, and in a 80 nascent or reactive state, the excess of formaldehyde is removed. This formaldehyde is reduced to its alcohol which is soluble in water and which is volatilized at the boiling temperature. Consequently, the formaldehyde if present in excess after having acted 85 upon the oils as an agent of purification is completely removed except for such small amounts as may have become combined with the oil with sufficient permanence to prevent removal by this process. The hydrogenation, in addition to removing the excess of formaldehyde, further purifies the oil and destroys impurities which impart color and bad odor to the oils, the hydrogen combining 90 with the unsaturated compounds. In this manner sulfur compounds are attacked and removed in a volatile form, sulfureted hydrogen being given off.

By the treatment of the oils with formaldehyde, combined with and followed by the hydrogenation of the oils, oils of a superior quality, and relatively free from color and odor, are obtained. By this process oils which can not be refined primarily by silicates or fullers' earth are converted into 100 products which can be subsequently refined 110

by silicates or fullers' earth, thus furnishing excellent qualities of odorless and colorless oils. The soy bean oil is of such a nature. Without the treatment of the present invention it is difficult to refine this oil by silicates or fullers' earth. After the treatment according to the present invention it gives a very valuable product upon refinement with fullers' earth.

10 Instead of employing the metal in a powdered form, it can also be used in the form of sheets and filings. If sheets are used they are hung or suspended in the boiling oil or fat. When zinc dust is used in the present

15 process a sort of zinc sponge is formed after the action has proceeded for sometime, this sponge forming lumps and preventing further generation of hydrogen. When this stage is reached the steam is turned off and

20 the oil allowed to rest, whereupon the impurities gather at the bottom and the oil becomes clarified.

The novel process of the present invention can be combined with, or used as a partial 25 substitute for, other processes of purification. Accordingly oil which has been subjected to the present process can be further treated by other processes, such as further hydrogenation, purification with fullers' 30 earth, etc.

The process of the present invention causes very small losses of oil and results in the production of superior oils and fats which are substantially free from impurities of a 35 gelatinous and albuminous nature and other objectionable impurities. The oil may also be to a greater or less extent saturated or hydrogenated, and unsaturated compounds present may at the same time be saturated 40 and partially or completely removed. It is usually advantageous to agitate the oil during this treatment except when it is desired to permit separation of the impurities to take place. This agitation is conveniently 45 effected by the use of steam coils opening below the surface of the oil, or near the bottom of the oil mass.

It is intended for the foregoing description to be illustrative of the invention. The 50 invention is not limited to this specific description. Varying amounts of formaldehyde can be used in this process, although for practical operations the amount used need be only that which is sufficient to completely free the oil of impurities, this amount 55 being advantageously added gradually instead of all at once as already described. Other processes of hydrogenation also can be used instead of that described which will

give the hydrogen in a nascent condition or 60 in such a reactive condition that it will accomplish the desired purification.

I claim:

1. The process of purifying oils which comprises heating the oils with direct steam 65 and with formaldehyde, and subsequently subjecting the oils to treatment with hydrogen.

2. The process of purifying oils which comprises heating the oils with direct steam 70 and with formaldehyde, and subsequently subjecting the oils to treatment with nascent hydrogen.

3. The process of purifying oils which comprises heating the oils with direct steam 75 and with the addition of formaldehyde sufficient to remove the gelatinous and albuminous impurities, and subsequently removing the excess of formaldehyde by treatment with nascent hydrogen.

4. The process of purifying oils which comprises heating the oils with direct steam and with the addition of formaldehyde sufficient to remove the gelatinous and albuminous impurities, and subsequently treating 85 the oils with a metal and acid to generate nascent hydrogen therein.

5. In the art of purifying oils, the process which comprises subjecting the oils to treatment with direct steam and with formaldehyde.

6. In the art of purifying oils, the process which comprises subjecting the oils to treatment with direct steam, formaldehyde and a metal and an acid which generate hydrogen.

7. In the art of purifying oils, the process which comprises subjecting the oils to the action of direct steam and gradually adding formaldehyde during such action until the gelatinous and albuminous impurities have 100 been precipitated.

8. In the art of purifying oils, the process which comprises treating the oils with formaldehyde, and removing any excess of formaldehyde by treatment with hydrogen.

9. In the art of purifying oils, the process which comprises treating the oils with formaldehyde, and removing any excess of formaldehyde by treatment with a metal and an acid which generate nascent hydrogen 110 therein.

In testimony whereof, I hereto affix my signature in presence of the witnesses.

DR. BELA LACH.

Witnesses:

ALFRED KLORB,
RUDOLF MESTIAN.
